UNITED STATES PATENT OFFICE.

FREDERICK A. TRAUT, OF BUFFALO, NEW YORK.

TRAP FOR CONDUCTOR PIPES.

Application filed July 30, 1925. Serial No. 47,030.

This invention relates to a trap for use in connection with a pipe whereby rain water is conducted from the roof of a building to the sewer pipe underground.

5 It is well known that sewers often become clogged by sticks, rags and similar refuse which is washed from the roof and carried by the conductor pipe to the sewer and on this account involving considerable expense 10 and labor in removing the obstruction.

The object of this invention is the provision of simple, inexpensive and efficient means for preventing such refuse from reaching the sewer and to that end consists 15 generally of means which are associated with the conductor pipe and serve to separate and detain any sticks, rags or the like but permit the clear water to pass to the sewer or drain and is so organized that the 20 same may be readily cleaned and also prevented from freezing in winter time.

In the accompanying drawings:—

Figure 1 is a vertical section of my improved trap for conductor pipes.

25 Figure 2 is a fragmentary cross section of the same taken on line 2—2, Fig. 1.

Figure 3 is a fragmentary vertical section, on an enlarged scale, showing the bend or safety by-pass for preventing water from 30 remaining in the trap and freezing in winter time.

Similar characters of reference indicate like parts throughout the several views.

The numeral 10 represents the lower end 35 or outlet of the conductor pipe which carries the rain water from the roof of the building and 11 the inlet or upper end of the drain or sewer pipe intended to receive the water. Between the conductor pipe and sewer pipe 40 any improved trap is arranged and in its preferred construction this trap, as shown in the drawings, is constructed as follows:—

The numeral 12 represents the upper pipe section of the trap which communicates at 45 its upper end with the conductor pipe 10, and 13 represents the lower pipe section of the trap which communicates with the sewer or drain pipe 11. The opposing parts 14, 15 of the upper and lower pipe sections are inclined from the upper pipe section toward 50 the lower pipe section for a purpose which will presently appear. The interior of this inclined passage is provided with an annular rearwardly facing shoulder 16 and in rear 55 of the lower part of this shoulder this passage is provided with a transverse upwardly

opening groove 17. This shoulder is engaged by the marginal part of the front side of a screen 18 which latter rests at its lower end in the groove 17 and is detachably connected at its upper end with said shoulder by a screw 19. On the upper side of the lower pipe section the same is provided adjacent to the rear side of the screen with a clean-out opening 20 through which the 60 screen may be removed for cleaning purposes when required, this clean-out opening being normally closed by a cap or plug 21 having a screw connection 22 with the lower pipe section.

The numeral 23 represents an upright catch pocket which is adapted to receive the refuse separated from the roof water. This pocket communicates at its upper end with that part of the underside of the inclined 70 passage which is formed in the upper pipe section and arranged immediately in front of the screen. The lower end of the pocket is provided with a removable closure consisting preferably of a cap 24 having a 75 screw connection 25 with the pocket.

Immediately above the lower end of the pocket the same is connected by relief means with the adjacent part of the lower pipe section so as to enable the water in the pocket to slowly drain out of the same into the lower pipe section. The preferred form of these relief means shown in the drawings consist of a boss 261 arranged on the exterior of the pocket and provided with an inner 80 reduced relief duct 26 opening into the pocket and an outer enlarged socket 27 having an internal screw thread and forming an outwardly facing shoulder 28, a relief pipe 29 of reduced diameter having a plain lower 85 end which projects through an opening 30 in the lower pipe section and having its upper part provided with an external flange 31 and arranged within the socket, a screen 32 arranged in the socket 27 between the 90 shoulder 28 and the flange 31, and a clamping sleeve 33 surrounding the relief pipe and bearing against the outer side of the flange 31 and having an external screw 95 thread engaging with the internal thread of the socket.

As the water descends in the upper pipe section it first fills the pocket and thereafter the water flows through the main screen 18 and is then conducted by the lower pipe section to the sewer. Any refuse, such as small sticks, rags, or the like, which may be washed 100

down from the roof by the rain is intercepted by the screen and prevented from reaching the sewer and clogging the same. Instead of this the sticks, rags and other refuse pass from the front side of the screen downwardly into the catch pocket wherein the same collects and may be removed from time to time upon first detaching the bottom closure 24. The removal of the refuse from the screen is facilitated by the incoming stream of water which, due to the downward inclination of the opposing parts of the upper and lower pipe sections containing the main screen, causes the refuse to be washed downwardly from the screen and into the catch pocket, thereby maintaining the latter constantly in the highest state of efficiency.

When the rain ceases the water in the pocket flows slowly out of the same through the reduced relief passage into the lower section of the conductor pipe, thereby avoiding the possibility of water freezing in the pocket in cold weather and damaging the trap. Sticks, rags and large particles are prevented from passing through the relief passage by the small screen therein and if the latter should become clogged it can be easily removed and cleaned upon first unscrewing the clamping sleeve.

I claim as my invention:—

1. A trap for conductor pipes comprising an upper inlet pipe section, a lower outlet pipe section, a screen arranged between said upper and lower pipe sections, a pocket having an inlet at its upper end which communicates with said upper pipe section in front of said screen, and a reduced relief pipe connecting the lower part of said pocket and said lower pipe section.

2. A trap for conductor pipes comprising an upper inlet pipe section, a lower outlet pipe section, a screen arranged between said upper and lower pipe sections, a pocket having an inlet at its upper end which communicates with said upper pipe section in front of said screen, a reduced relief pipe connecting the lower part of said pocket and said

lower pipe section, and a screen arranged in the passage through said relief pipe.

3. A trap for conductor pipes comprising an upper pipe section, a lower pipe section communicating at its upper end with the lower end of the upper pipe section, the passage in the opposing parts of said pipe sections being provided with a rearwardly facing annular shoulder and a transverse groove adjacent to the lower part of said shoulder, a screen arranged in said passage and engaging the marginal part of its front side with said shoulder and resting with its lower part in said groove, a screw connecting the upper part of said screen with said shoulder, said lower pipe section being provided in its upper part adjacent to said shoulder with a clean-out opening through which the screen may be removed, a screw plug for closing said clean-out opening, and a catch pocket having its upper end communicating with the underside of said upper pipe section adjacent to the front side of said screen.

4. A trap for conductor pipes comprising an upper pipe section, a lower pipe section, a screen arranged between said upper and lower pipe sections, a catch pocket communicating at its upper end with the lower part of said upper pipe section adjacent to the front side of said screen, and relief means for slowly draining the water from the pocket into said lower pipe section comprising a boss arranged externally on the lower part of the pocket and containing an inner relief duct and an outer enlarged socket forming an internal outwardly facing shoulder, a relief pipe having a lower part projecting through said lower pipe section and an external flange at its upper end arranged within said socket, a screen arranged between the flange of said relief pipe and the shoulder in said socket, and a clamping sleeve surrounding said relief pipe and bearing against the flange thereof and having a screw connection with said boss.

In testimony whereof I affix my signature.

FREDERICK A. TRAUT.
